UNITED STATES PATENT OFFICE.

JOHN W. RADU, OF NEW YORK, N. Y., ASSIGNOR TO WESTERN ELECTRIC COMPANY, INCORPORATED, OF NEW YORK, N. Y., A CORPORATION OF NEW YORK.

VACUUM-TUBE SOCKET.

Application filed November 11, 1920. Serial No. 423,244.

To all whom it may concern:

Be it known that I, JOHN W. RADU, a citizen of the United States, residing at New York, in the county of New York and State of New York, have invented certain new and useful Improvements in Vacuum-Tube Sockets, of which the following is a full, clear, concise, and exact description.

This invention relates to a socket for vacuum tubes and more particularly to a socket for vacuum tubes such as the audion in which a plurality of electrodes are arranged on the base of the tube and with which electrodes intimate connection must be made for the various circuits.

In sockets for vacuum tubes it has heretofore been a common practice to attach all contact members of the socket to one end thereof and arrange said members substantially parallel to each other. Such arrangement allows the development of a considerable electro-static capacity between the various contact members. Such an electro-static capacity between the contact members seriously impairs the efficiency of a vacuum tube mounted in such socket regardless of the type of circuit in which the tube is employed.

An object of this invention is a socket which will be convenient for use and effective in making such contacts as are required and in which the arrangement of the contact members is such that the electrostatic capacity between them is reduced to a negligible factor.

The invention will be better understood by reference to the following specification and the accompanying drawing in which Fig. 1 shows a socket designed according to this invention in combination with an audion. Fig. 2 shows a view from below of the socket shown in Fig. 1.

Referring in particular to Fig. 1, 10 represents a preferably rectangular base member composed of a single molded piece of insulating material, preferably that known in the art as bakelite. The base member has extending vertically therethrough an opening 11 from the bottom of which four channels 12 lead to the exterior of the base member. The inner ends of these channels are arranged substantially radially of the opening through the base member and the outer ends are preferably so directed that the channels emerge in pairs from opposite sides

of the base member 10. Arranged in the aforementioned opening and molded therein is a tubular member 13, preferably formed from a piece of seamless brass tubing in which is provided the bayonet slot 14. In 60 the corners of the base member 10 are molded tubular elements 15 which project slightly above the surface of the base member and which extend to the bottom of the channels 12 intermediate to the ends thereof. The elements 15 are threaded interiorly throughout their length for a purpose to be later described. Arranged in the channels 12 are the spring contact members 16, 17 and 18 which are of the same configuration as the channels 12 and which are attached to the base by means of screws 19 passing therethrough and engaging with the threads of the elements 15. The inner ends of the contact members 16, 17 and 18 extend 65 under the opening in the base and are arranged substantially radially thereof. The terminals 20, 21 and 22 of said members 16, 17 and 18 are arranged at the corners of the square, the center of which coincides with 70 the axis of the tubular member 13. The outer ends of the contact members 16, 17 and 18 are provided with apertures through which wires may be passed and soldered to 75 said members to constitute a permanent connection. By means of screws 23 arranged in the upper ends of the elements 15 wires may be temporarily attached to these elements.

Arranged at the corners of a square on the base 24 of the vacuum tube 25 adapted to cooperate with this socket are provided electrodes 26 which are electrically connected with the cathode 29 of the tube and electrode 27 which is in electrical connection with 80 the control element 30 and the electrode 28 electrically connected with the anode 31. These electrodes are adapted to cooperate 85 with the contact members of the socket to bring the cathode electrodes into engagement with the terminals 20 of the contact member 16, the control element electrode into engagement with the terminal 21 of the contact member 17 and the anode electrode into engagement with the terminal 22 of the contact member 18. Although the preferred 90 arrangement of the electrodes and contact members is as shown with the cathode contact members attached to the base at one end, and the grid and anode contact members 95

attached at the other end, it is to be understood that this arrangement may be varied as may be necessary. Also a pin 35 is provided on the base 24 which pin engages with 5 the slot 14 in the member 13 to hold the tube in the socket and the electrodes 26, 27 and 28 in position to be engaged by the terminals of the contact members.

The base member 10 of the socket is a single piece of insulating material and is formed by a molding operation. The tubular member 13 and the elements 15 are molded into the base member during the formation thereof. The molding of these elements into the base member produces a practically integral structure in which the various metallic portions are completely insulated from each other. The base itself being of insulating material obviates the use 15 of insulating strips in the attaching of the contact members and the material of the base is sufficiently strong to withstand the service to which it may be put.

The arrangement of the contact members 20 on the socket and more especially where the contact members are arranged radially of the opening through the socket is such that they are spaced apart the maximum distance

consistent with a compact and effective socket structure thereby reducing to a practical 30 minimum the electro-static capacity therebetween and allows the contact members to emerge in pairs from opposite ends of the base member of the socket and also gives to the contact members a highly effective 35 spring length.

What is claimed is:

A vacuum tube socket comprising a base of insulating material a tubular socket member arising therefrom, a plurality of tubular members mounted in said base, a plurality of flat spring contact members, each of said contact members having one end projecting across one end of said socket member and the other end projecting beyond the edge of the 40 base, a bolt extending through each of said contact members and being threaded into one end of a tubular member to attach said contact member thereto, and a second bolt threaded in the opposite end of each of said 45 tubular members to provide means for attaching an electrical conductor thereto.

In witness whereof, I hereunto subscribe my name this 9th day of Nov. A. D., 1920.

JOHN W. RADU.
